ABSORPTION REFRIGERATING APPARATUS

Application filed February 7, 1929. Serial No. 338,177.

This invention relates to refrigerating apparatus of the intermittent absorption type.

The object of this invention is to improve the construction and operation of refrigerators or iceboxes employing the absorption principle with particular reference to the construction and arrangement of the evaporator and the arrangement of its parts in suitable compartments or chambers for the purpose of carrying over from one refrigerating period to the other with as slight a rise in temperature as possible during the lapse of refrigeration, or in other words, during the heating period.

Briefly stated, the foregoing object is accomplished by providing the refrigerating chamber casing with an upper storage compartment separate from the refrigerating chamber and adapted to receive a refrigerant storage, the insulation between this chamber and the refrigerating chamber being heat insulating but less effective than the normal heat insulation on the outside of the box to permit a slow transfer of heat through the insulation and into the storage compartment from the refrigerating compartment, the rate of transfer delaying any passage of heat during the heating period from the storage to the refrigerating compartment.

In the further development of the object of the invention the upper part of the refrigerating chamber below the storage compartment is provided with a heat absorber in the form of a somewhat shallow pan extending across the box from one side to the other and near the back with an integral depressed pan portion or casing closed at the top and communicating with the more shallow forward portion. The depression of the rear pan portion provides an open space above it and to the rear of the front portion for the circulation and collection of hot air from the refrigerating chamber. This entire pan contains a quantity of heat absorbing liquid which preferably may be water adapted to freeze

into a cake of ice to form a flywheel for carrying over from one refrigerating period to the other. Below the bottom of the rear pan portion and the front pan portion is a refrigerating unit or grid also arranged in an upper rear and lower front grid portion, the rear portion being baffled to provide a circuitous route for the refrigerant, either liquid or gas, as it flows to and from the storage, this circuitous route being connected in parallel to the forward portion of the grid. The rear upper portion engages the underside of the rear tank portion and is, therefore, in close heat conducting relation with respect to it, so that the heat of any refrigerant passing from the storage to the grid could be readily absorbed and at the same time the flywheel may readily absorb any heat present in the box. The forward lower grid portion is spaced from the bottom of the forward portion of the pan to provide a chamber for ice cube containers. Below and at the front the grid is provided with a suitable heat insulating floor or partitions provided with a lip in front of the grid and serving to permit free access at the front of the box to the cube container compartment. This cube container compartment is closed by a suitable inner door which may be swung downwardly when the main refrigerator door is open. At the rear of the box and of the ice cube compartment just described, is an additional ice container structure comprising a support hinged at the back of the box and adapted to swing up and latch to the underside of the ice cube compartment. This hinged support, when in proper position, sustains a relatively large ice pan which has its mouth nesting up about the rear portion of the heat absorber and extends about the upper rear grid portion. A cover is suitably supported inside of the rear pan portion and in a position to engage the underside of the upper rear grid portion so that when the pan is filled with water up to this cover, heat may be transferred readily

from the water in the pan to the grid resulting in the freezing of the water in this pan and causing it to assist the flywheel operation of the other pan and absorb heat from the grid during the heating period and heat from the box. This bulk ice container not only furnishes a convenient supply of ice for an icing emergency but also functions as a part of the heat absorber of the flywheel.

10 The features of the invention thus far brought out and possibly others will be readily understood from the following description, drawings and claims.

Referring now to the drawings, Fig. 1 is 15 a vertical section of the box looking from the side; Fig. 2 is a rear elevation showing the circuit; Fig. 3 is a front view of the upper portion; Fig. 4 is an enlarged sectional view looking from the side and showing a 20 modified form of ice cube arrangement; and Fig. 5 is a top plan view of the refrigerating element or grid.

In the arrangement shown in the drawings, the box comprises a lower apparatus 25 casing 1 having an access opening at the front and a draft opening at the bottom. This bottom opening is preferably of the complete area of this compartment. Extending from the front near the bottom toward the top of 30 this compartment is a flue plate 2 separating from this apparatus compartment a flue chamber 3 which is open to the bottom of the refrigerator on the one hand and to the back of the box as will appear. Supported 35 in this apparatus compartment is a heat insulated refrigerating casing 4 having an upper downwardly extending skirt 5 at the front. Between this skirt and the bottom of the refrigerating casing is an opening 40 closed by a suitable door 6 of the usual form. The skirt 5 forms an upper storage chamber 7 at the top and this is closed by plate 8 of heat insulating material secured in place in any suitable manner. This plate 8 while it 45 is heat insulating on the one hand, it nevertheless should permit some transfer of heat through it to dispose of some of the heat in the box.

Any suitable intermittent refrigerating 50 circuit may be used but a suitable intermittent absorption circuit is shown in Figs. 1 and 2, and it comprises an air-cooled condenser element 9, a cylindrical still 10 arranged horizontally, a cooling loop structure 55 generally indicated at 11 and communicating by conduits 12 and 13 with the still all arranged in the apparatus compartment. The still may be provided with a suitable burner 14. The top of the still communicates with 60 a gas outlet and rectifying loop in the form of a pipe 15 which passes up at the back of the box to the top in a rectifying flue 16 and thence downwardly into and near the bottom of a closed trap casing 17. This trap 65 casing has a pipe 18 extending out of its top

and connected as at 19 to the top of the condenser element. The trap casing 17 is also provided with a pipe 20 extending out of its side about one-third of the way down and leading to the two conduits 12 for returning the gas to the loop during the refrigerating period.

70 The flue portion 3 communicates with the main flue 21 extending up the back of the box and open at the top.

The lower part of the condenser is connected by a pipe 22 with branches leading to the top of a refrigerant storage 23 of substantially annular form, either square or circular, in the storage chamber 7. Extending 75 downwardly from the storage 23 is a refrigerant grid supply pipe 24 connected to the refrigerating unit or grid shown in top plan in Fig. 5 and described hereinafter more in detail. The lower part of this grid communicates by a pipe 25 with a suitable liquid refrigerant sustaining trap 26 of any preferred form. The pressure in this trap is equalized with the pipe 22 by a cross connection 27. This trap may be of any preferred 80 form but must be capable of sustaining the proper head of liquid refrigerant in the entire evaporator structure including its storage and its grid and yet must be capable of bypassing back to and through the pipe 22 85 any boiler liquor which may be entrained with the gas and collected in the evaporator. 90

The absorption circuit thus far described has a very familiar operation in that during 95 the heating period gas passes from the still through the rectifying loop to the bottom of the trap and below the surface of the liquid collected therein. It bubbles up through the 100 liquid in the trap and passes by the condenser pipe 18 to the top of the condenser which it enters and in which it is condensed and flows through the pipe 22 to the evaporator storage at the top of the refrigerator. The liquid refrigerant collects in the entire evaporator 105 apparatus and at the end of the heating period and after the proper cooling of the apparatus returns through the pipe 22 to the condenser, thence to the trap and back 110 through the loop pipe 20 to the loop where it initiates boiler liquor circulation through 115 the loop and promotes cooling and absorption. The various cooling and heating effects necessary for the proper operation of the absorption system are brought about by the flue arrangement.

120 The foregoing description has set up the general construction and type of refrigerator and the description will now proceed with that part of the invention which relates to the arrangement of the heat absorber and the ice cube compartments which serve to prevent all heat effects within the refrigerator raising the temperature of the refrigerating compartment and ice cubes during the 125 heating period.

Below the evaporator storage and its compartment is a heat absorber in the form of a forward somewhat shallow central pan portion 28 having side liquid or water legs 28' extending downward the depth of the ice cube compartment as will appear. This forward portion extends from one side of the box to the other and opens down at the back in a long narrow conduit 29 the full width of the box, to a closed rear pan or casing 30 which also extends from one side to the other of the box. This rear pan or casing 30 may be deeper than the pan portion 28 and both are filled with water which extends to a point near the upper edge of the pan portion 28. This rear pan portion 30 is closed at its top and there is an air chamber 30' formed above it and to the rear of the forward portion 28 to provide a heated air circulating and collecting chamber. The rear pan portion is the same in dimension across the box as the forward portion as shown in Fig. 3, and the housing for the cube chamber, to be described, stops at the rear end of the forward pan portion 28 so that vertical side flues are formed past the rear pan portion 30 to the chamber 30'.

Below this heat absorber is a refrigerating unit or grid which comprises, as shown in Fig. 5, a tubular rectangular grid structure consisting of side tube headers 31 and 32 and cross-connecting tubes arranged in a forward group of pipes 33, and a rear group 34, the rear group being raised as a group in a horizontal plane above the plane of the group 33 by upwardly bending the headers 31 and 32 at 35 and 36. The refrigerant supply pipe 24 from the storage enters the grid at 37 for example, passes along the back pipe 34 to the left header 31 where it passes forward and is blocked at 38 so that it must pass by the second pipe 34 to the right-hand end where it loops again and returns by the third pipe header 32, being blocked at 39. As the gas passes through the third pipe from right to left, its joint with the header 31 establishes a parallel connection through the balance of the grid, and passes out to the pipe 25 at the right-hand lower corner as shown. The upper rear portion of the refrigerating grid is supported against the bottom of the rear pan or casing 30 so as to be in intimate heat transfer relation with respect to it.

The forward lower grid portion is supported upon the floor 40 of a heat-insulating housing having an upwardly extending lip 41 extending along the front of the grid. This housing also includes side walls 40' and a rear wall 40'. Between this forward portion of the grid the bottom of the forward pan portion 28 and its legs 28' is an ice-cube compartment for ice-cube containers 42. The front edge of the pan portion 28 is provided with a suitable stop strip 43 and the opening 65 to the ice-cube compartment thus formed is

closed by a suitable inner door 44 which is hinged at 45 along its lower edge. The ice-cube compartment and its floor or partition 40 extend from one side of the refrigerating chamber to the other and stop short of the rear at substantially the front of the pan portion 30 as shown. In this space there is a bulk ice container pan 46 open at the top and notched at 47 and 48, Fig. 3, at the front, to permit the passage of the headers 31 and 32 therethrough. It is also notched at the front to receive the pan 30 as shown in Fig. 4. The sides and back of this bulk ice container nest nicely about the pan or casing portion 30 so that the heat absorbing characteristic of the upper rear portion of the grid is nicely confined to the flywheel absorber portion 30 and to the bulk pan 46. If desired the bulk pan 46 may be provided with cleats 49 at its end supporting a cover 50 which extends into the pan and has raised curved recesses 51 which receive the grid coils. This cover is of such a shape that portions of it extend below the surface of the liquid in this bulk container 46 and permit ready transfer from the container and liquid to the grid. This bulk container 46 is preferably removable by downward and outward movement and may be held in place by any suitable mechanism, the arrangement shown being in the form of hinged brackets which swing from the back of the box to a supporting position under the container 46.

It will be seen from the foregoing that during the cooling period the heat absorber, comprising the pan portions 28 and 30, will be frozen. The cubes in the cube containers 42 will also be frozen and likewise the water in the bulk container 46. When the refrigerating cycle ceases and the heating period begins, any heat present in the liquid refrigerant delivered to the storage and passing to the grid will be absorbed by the flywheel and the bulk container and therefore prevented from reaching the ice cubes. Also any heat present in the box will pass up about the bulk container and the rear portion of the heat absorber and collect in the heat collecting chamber 30' from which it will be absorbed by the flywheel and the bulk container ice. It will also be seen that the ice cubes are always between the freezing coils of the grid below and the ice flywheel above and protected against melting during the heating period. In this way the temperature of the box will be maintained with little or no variation during the heating period and the ice cubes will be kept intact ready for use.

In the modification shown in Fig. 4 the partition 40 is moved down to provide an additional ice cube compartment 55 below the grid coils 33 for containing another ice cube pan or container 56. The back of this compartment may be suitably closed if desired by a heat insulating wall 57.

What I claim is:

1. In a refrigerating apparatus of the absorption type, a cabinet comprising a casing having a refrigerating chamber and an upper refrigerant storage chamber heat insulated from the refrigerating chamber, a refrigerant storage in said storage chamber, a heat absorber adjacent to and below the storage compartment and comprising a forward portion extending substantially from one side of the box to the other and a rear portion communicating therewith, an ice cube insulating housing extending downward from said heat absorber, and a refrigerating element having a portion in heat transfer relation with the rear portion of said heat absorber and another portion in the bottom of said ice cube compartment, and ice cube containers arranged in said ice cube compartment 20 between the refrigerating elements therein and said heat absorber.

2. Refrigerating apparatus as in claim 1 wherein the heat absorber is in the form of a pan extending across the refrigerating chamber and communicating with a lower closed casing at the rear to provide a heat collecting chamber above and at the rear.

3. Refrigerating apparatus as in claim 1 wherein the heat absorber is in the form of a pan extending across the box with downwardly extending legs at the sides and a depressed closed rear portion in liquid communication with the front portion.

4. Refrigerating apparatus of the type set forth in claim 1 wherein the refrigerating element is in the form of a grid including a horizontal row of tubes in heat transfer relation with the rear portion of said heat absorber and a depressed front row spaced from the bottom of said forward portion of the heat absorber, the latter to provide a space for ice cube containers.

5. Refrigerating apparatus of the type set forth in claim 1 wherein the refrigerating element is in the form of a grid including a horizontal row of tubes in heat transfer relation with the rear portion of said heat absorber and a depressed front row spaced from the bottom of said forward portion of the heat absorber, the latter to provide a space for ice cube containers, and another container for freezing liquid arranged below and in heat transfer relation with respect to the refrigerating coils below the rear portion of said heat absorber.

6. Refrigerating apparatus of the type set forth in claim 1 wherein the refrigerating element is in the form of a grid including a horizontal row of tubes in heat transfer relation with the rear portion of said heat absorber and a depressed front row spaced from the bottom of said forward portion of the heat absorber, the latter to provide a space for ice cube containers, and another container for freezing liquid arranged below and in

heat transfer relation with respect to the refrigerating coils below the rear portion of said heat absorber, comprising a pan extending up about the coils and nesting about the rear portion of the heat absorber, and a cover within said bulk pan and provided with portions extending into the liquid therein and other portions contacting with the coils of the refrigerating element.

In testimony whereof I hereby affix my signature.

EDMUND E. ALLYNE.
